UNITED STATES PATENT OFFICE.

EDGAR H. FREEMAN, OF TRENTON, NEW JERSEY, ASSIGNOR, BY MESNE ASSIGNMENTS,
TO TRENTON PORCELAIN COMPANY, A CORPORATION OF NEW JERSEY.

DIVIDED INSULATOR.

1,147,498.

Specification of Letters Patent.

Patented July 20, 1915.

Application filed November 1, 1912. Serial No. 729,171.

To all whom it may concern:

Be it known that I, EDGAR H. FREEMAN, a citizen of the United States, residing at Trenton, in the county of Mercer and State 5 of New Jersey, have invented certain new and useful Improvements in Divided Insulators, of which the following is a specification.

The present invention relates to certain 10 new and useful improvements in the construction of insulators such as are adapted to be employed for supporting electric-wires or similar members which are strung along a ceiling, wall, or like support.

15 The object of the invention is to provide an insulator of this character which is comparatively simple and inexpensive in its construction, which can be readily assembled and secured in position, and which will 20 surely grip and hold the wires.

A further object of the invention is to provide an insulator formed in complementary and interchangeable parts which are 25 peculiarly constructed so as to eliminate all possibility of a short circuiting of the wires, and which will not injure the insulation upon the wires.

With these and other objects in view, the 30 invention consists in certain novel combinations and arrangements of the parts as will more fully appear as the description proceeds, the novel features thereof being pointed out in the appended claim.

For a full understanding of the invention, reference is to be had to the following 35 description and accompanying drawing, in which:—

Figure 1 is a perspective view of an insulator constructed in accordance with the 40 invention, the parts being shown as assembled. Fig. 2 is a side elevation of the insulator, the parts thereof being separated. Fig. 3 is a longitudinal sectional view 45 through the insulator. Fig. 4 is a detail perspective view of one of the parts of the insulator, and Fig. 5 is a plan view of one of the parts of the insulator.

Corresponding and like parts are referred 50 to in the following description and indicated in all the views of the drawings by the same reference characters.

Specifically describing the present embodiment of the invention, the numerals 1 and 2 designate the two complementary

halves or sections of the insulator, the said 55 insulator sections being formed of porcelain or other suitable material, and being identical in construction so as to be interchangeable.

The fact that the two sections or parts of 60 the insulator are interchangeable, as above mentioned, is advantageous, since it enables an operator to easily and quickly assemble the insulators without the necessity of selecting special parts, and since it also eliminates the waste which would be incident to 65 having a number of special parts left over without the necessary coöperating parts to form complete insulators. The sections 1 and 2 of the insulator are shown in the present 70 instance as so formed as to impart a substantially cylindrical shape to the assembled insulator, although it will be obvious that the insulator might be given any other exterior shape or configuration without departing from the spirit of the invention. 75

Each of the complementary sections of the insulator is formed with a base 3 which is substantially cylindrical in shape and has 80 an axial opening or bore 4 therein.

Projecting from the inner face of the base 3 and disposed on one side of the bore or axial opening 4 is an extension 5, the said extension having a cross sectional area 85 which is substantially equal to one half of the cross sectional area of the base. The outer side wall of the extension 5 is a continuation of the outer wall of the base 3, while the inner side wall 6 of the extension 90 is on a median plane of the base 3.

Projecting from the inner face of the base 3 and surrounding the bore 4 is a boss portion 7, the length of the said boss portion being preferably about one half the 95 length of the extension 5, and the said extension being provided upon the inner side thereof with a recess 8 which is in substantial alignment with the boss portion 7 so as to receive the boss portion of the opposite 100 insulator section when the two sections are assembled. In the present instance the boss portions 7 and the recesses 8 are shown as tapering toward the ends thereof, since such a construction facilitates to a certain extent 105 the assembling of the insulator sections. The tapering characteristic of the bosses 7 is of practical importance in the feature of

wedging the wire outward into the semi-circular wire receiving grooves disposed about the base portions of the bosses.

The exposed inner face of the base 3 is formed with a curved and substantially semi-circular depression 9 which extends around the boss portion 7, the base of the said depression 9 having the radial ribs or teeth 10 projecting therefrom. It will also be observed that the extremity of the extension 5 is provided with a curved groove 11 which extends around the recess 8, the ends of the groove communicating with notches 12 in the sides of the extension, and the base of the groove being provided with the transversely disposed and parallel ribs or teeth 13. It may also be mentioned that the middle or intermediate portion of the groove 11 is shallower and of less depth than the end portions of the groove.

In assembling the two sections 1 and 2 to provide a complete insulator, the extensions 5 of the two sections are arranged side by side with the inner faces 6 thereof abutting against each other, the boss portion 6 of each member being received within the recess 8 of the opposite member, and the end of each of the extensions 5 being disposed opposite the face of the base member 3 of the other section. The bores or axial openings 4 of the two insulator sections are then in registry with each other, and a screw or other suitable fastening member can be inserted through the same. The wires or conducting members are inserted between the ends of the extensions 5 and the exposed inner faces of the bases 3, the said wires extending through the notches 12 and being curved laterally around the boss portions 7 so as to fit within the corresponding grooves 9 and 11 of the two members. Owing to the fact that the intermediate or middle portions of the grooves 11 are shallower than the end portions of the grooves 11 it will be obvious that the shallow portion of the groove will tend to force the wire securely into the groove 9, the teeth 13 and 10 of the respective grooves gripping the wire so as to ob-

tain a firm hold thereon. These teeth 13 and 10, it will be observed, engage opposite sides 50 of the wire, and are arranged at angles to each other so as to act in a very effective manner to grip the wire. The boss portion 7 of each of the insulator sections will serve to interlock with the recess 8 of the opposite 55 insulator section to hold the two insulator sections against that lateral displacement which might be caused by the tension in the wires or conductors, and after the screw or fastening member which has been inserted 60 through the bores 4 of the sections has been tightened, the two insulator sections will be held securely in position. It is also desired to direct attention to the fact that the boss portions 7 of the insulator sections are always interposed between the conductors and the screw or fastening member employed for holding the insulator sections in position, thereby eliminating any possibility of the conductor being brought into contact with 70 the screw, or even being brought so close to the screw as to render the passage of sparks a possibility. The two conductors are thus securely gripped and held in position without danger of sparking or short circuiting. 75

Having thus described the invention, what I claim as new and desire to secure by Letters Patent, is:—

A split knob insulator comprising duplicate interchangeable members, each having 80 a circular base portion, an extension projecting from one side of the base parallel with the longitudinal axis of the insulator, and an integral tapered cylindrical boss projecting centrally from the inner face of the 85 base alongside of the said extension, each member being further provided with a semi-circular wire receiving groove extending about the larger base portion of the boss.

In testimony whereof I hereunto affix my 90 signature in the presence of two witnesses.

EDGAR H. FREEMAN.
